CLAIM

The ornamental design for a food container with two compartments, as shown and described.

DESCRIPTION

FIG. 1 is a top plan view of a food container with two components showing my new design;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a top, front perspective view thereof.

The narrow rectangles bound by three broken lines and a solid line in FIG. 2 are features of the food container with two compartments that form no part of the claimed design.
